UNITED STATES PATENT OFFICE.

GEORGE M. HINKLEY, OF MILWAUKEE, WISCONSIN, ASSIGNOR, BY MESNE ASSIGNMENTS, OF ONE-HALF TO ALLIS-CHALMERS COMPANY, A CORPORATION OF NEW JERSEY.

BAND-SAW MILL.

SPECIFICATION forming part of Letters Patent No. 780,425, dated January 17, 1905.

Application filed May 2, 1901. Serial No. 58,514.

To all whom it may concern:

Be it known that I, GEORGE M. HINKLEY, a citizen of the United States, residing at Milwaukee, in the county of Milwaukee and State 5 of Wisconsin, have invented certain new and useful Improvements in Band-Saw Mills, of which the following is a specification.

My invention pertains to band-saw mills, and has for its primary object the vertical adjustment of the upper band-carrying wheel through a range or distance sufficient to bring it near to though clear of the log or cant whatever the size of the latter may be and without changing the elevation or adjustment 15 of the lower or driving wheel, so that the cutting stretch or length of the saw may be kept as short and as taut as practicable and the employment of saw-guides may be rendered unnecessary. This result I attain 20 by providing a third band-wheel, essentially like the usual upper wheel preferably, and so arranging said third wheel that it shall maintain constantly a proper and approximately uniform tension upon the saw blade or band. 25 A mere idler bearing against the upgoing side of the saw blade or band is not broadly new; but to fulfil the requirements of a mill of this character various conditions must be considered and special provisions must be made, as 30 will be explained hereinafter.

In the more common types of band-mills two wheels are employed, the lower carried by a shaft turning in fixed bearings and the upper one by a shaft turning in bearings 35 having a limited vertical adjustment and pressed upward by suitable weight-and-lever mechanism to maintain due tension upon the band. Such constructions necessitate the employment of guides above the log or cant to 40 prevent vibration or "whipping" of the blade and consequent irregularity of cut. To obviate the necessity for such guides and attain other desirable ends, a construction has been devised and patented wherein the band-carrying mechanism, including both the upper and lower wheels, is bodily elevated and lowered to bring the upper wheel close to the log or cant, the vibration of the saw after passing

through the same being unimportant, if occurring, and less likely to occur because that portion of the blade is closely approaching the lower or driving wheel. My invention will therefore be seen to pertain rather to the latter than to the former construction, though differing from the latter in employing fixed 55 bearings for the lower-wheel shaft and maintaining a short blade-section below the log or cant or between it and the driving-wheel.

Various novel features of construction incidental to the general plan thus outlined will 60 be explained in the ensuing description with the aid of the accompanying drawings.

In said drawings, Figure 1 is a side elevation, with portions broken away, of a band-saw mill embodying my invention in a preferred form. 65 Fig. 2 is a front elevation of the same with the saw-blade partially broken away; Fig. 3, a rear elevation of the upper portion of the mill; Fig. 4, a side elevation of the swing-frame, showing also a trussed controlling-lever therefor; Fig. 5, a top plan view of the cross girth or brace for the main frame; Fig. 6, a detail view of one of the adjustable boxes or bearings for the swing-frame; Fig. 7, an enlarged view of the adjusting mechanism 70 for the boxes of the upper band-wheel shaft; Fig. 8, a view illustrating a modified form of 75 tension mechanism.

The framework of the mill is susceptible of considerable variation, but must be such that 80 the upper band-wheel may be dropped as low or carried as high as required by logs or cants of any size which the mill is designed to cut. It is essential, too, that the frame be so braced or of such proportions and design as to give 85 due rigidity and prevent injurious vibration of any of its parts, and care is especially required to prevent the third wheel from twisting or getting out of proper plane, and thereby causing the saw blade or band to take a wrong 90 path or to enter into contact with the upper wheel out of proper line or too far forward or backward thereon. The importance of this will be appreciated when it is borne in mind that the blade travels at a speed of approxi- 95 mately two miles per minute and that it is

held to its proper working position solely by the adjustment of the wheels and direction of the blade thereto and therefrom, a slight inclination of the band-wheel shafts in a vertical plane causing the blade to run to the front or the rear of the wheel-rim and a like horizontal adjustment of the shafts also effecting a variation of position of the blade on the wheels.

10 Referring now to the drawings, I shall explain a preferred embodiment of my invention and shall thereafter describe some of the many variations that may be made in carrying the same into practice.

15 A indicates a substantial base or bed suitably fashioned to rest upon timbers B or other support at or about the floor-level of the mill-building, said base being preferably carried forward and adapted to receive the slabs and 20 boards or planks cut from the log or cant. A saw-guide C is advisably located at the forward edge of said base, as shown in Fig. 1, its upper end being just below the top line of the log-carriage D, which travels on tracks 25 past the saw, as usual; but the guide is not essential.

Beneath the bed or base A are yokes or hangers E, in which are adjustably mounted boxes or bearings F, designed to carry the 30 main driving-shaft G, with its belt wheel or pulley H and lower or driving band-wheel I, as usual.

Rising from the base or bed A is an upper frame comprising two side plates or castings 35 J, connected near their upper ends by a strut or cross-brace K, preferably of the form shown in Fig. 5. This brace, being the main cross tie or connection for the top of the frame, should be of such design and dimensions as to

40 insure great strength and rigidity. Hence it has inwardly-extending arms which, passing on opposite sides of the upper band-wheel, are bolted to the side plates or frames well inward, as indicated by dotted lines in Fig. 1 and by 45 full lines in Fig. 5. Each side plate or casting J is formed with an overhanging top and with a socketed boss a', between which extends a vertical standard or column L. These standards or columns are preferably seated at their

50 lower ends in the socketed bosses a' and are bolted or otherwise made fast to the overhanging tops of the side plates or frames J, as shown, though they may be otherwise held, if desired. Their purpose is to guide and sustain vertically-movable slides M, which carry the boxes or bearings for the shaft O of the upper saw-carrying wheel P. The slides M are of considerable length to give a long bearing and guiding support and to prevent cramping 55 or binding, and at the lower end of each below the wheel P there is formed a box or bearing. Extending across the space from slide to slide and journaled in these two bearings is a shaft Q, carrying pinions a, which

60 b on the forward faces or edges of the side plates or castings J of the upper frame of the mill, as seen in Figs. 1, 2, and 7. Keyed or otherwise made fast upon the shaft Q is a worm gear-wheel R, advisably contained within 70 a shell or casing S, cast with or secured to one of the slides M. As best shown in Fig. 7, a worm or screw T is carried within the same casing S, which is formed with an offset or space therefor, its upper and lower ends 75 bearing against plane surfaces formed for that purpose within the offset.

U indicates a vertical shaft which passes through and is guided in openings in the top and bottom of the offset of the shell, passing 80 also axially through the worm or screw T. The shaft is grooved or splined, and the worm is splined or grooved, or the shaft and the opening in the worm are made polygonal, so that the two parts shall be caused to rotate in 85 unison, while the worm is free to slide vertically upon and relatively to said shaft. The lower end of the shaft U is stepped or swiveled in a suitable bearing at its lower end and is connected, by bevel-gearing c d, Fig. 7, with 90 a horizontal shaft V, which is here represented as extending to a motor W of any suitable character, by which it may be turned as required, though of course it may be manually rotated, if preferred, in which case a winch 95 or hand-wheel will be provided, as is common in this class of machinery. The worm T is held in mesh with worm-wheel R by the shaft U, and when the latter is turned vertical motion is imparted, through the worm-gear, the 100 shaft Q, and pinions a a, meshing with racks b, to the slides M, and in this way the upper band-wheel shaft and its wheel are elevated or lowered, as required.

To provide for properly leveling or tipping 105 the shaft O, its boxes N are carried in yokes X, having vertical shanks or stems guided in boxes formed upon the slides M, said shanks or stems being tapped to receive heavy adjusting-screws X', the lower ends of which 110 rest upon brackets e, also formed upon the slides M, as seen in Figs. 1, 2, and 8. The boxes N, which carry shaft O, are free to tip in their yokes and are adapted to be adjusted horizontally toward and from the upright 115 frame-plates J in a manner well understood.

The range of movement provided for the slides M is such as will permit wheel P to be carried upward clear of the largest log or cant that the mill is designed to handle and 120 to fall as low as may be desirable in sawing the smallest log, cant, or timber.

It is always desirable to provide tension devices for maintaining a uniform strain upon the saw and to prevent overstraining thereof 125 when placing and adjusting the saw upon the wheels. It will readily be seen that with screws and other powerful adjusting devices there would be danger of applying undue strain to the saw if there were no automat- 130

ically yielding device adapted to limit the possible tension, and though other theories have often been assigned this is the real purpose and office of such automatic tension devices.

Under the present construction I provide automatic tension mechanism which, in addition to the function just noted, serves to take care of the very considerable portion of the 10 blade, which would otherwise become slack when the wheel P is lowered. A mechanism of this sort in order to be efficient and to avoid injury to the blade should embody a large guiding and supporting wheel for the 15 blade, and this should be so mounted, held, and guided as to preclude any twisting or deflection, as slight deviation from a proper plane of travel would cause the saw-blade to contact with wheel P too near the front or the 20 rear face thereof or at an angle, and consequently to take an improper position thereon. This matter of properly directing the blade to the upper wheel is of especial importance in mills of this type, in which an upper saw- 25 guide is usually dispensed with, such being, in fact, one of the leading objects of the vertical movement of the wheel other than mere adjustment for tension. In view of the requirements noted and in order to meet these 30 and at the same time maintain a substantially uniform tension upon the blade I provide the special tension and take-up mechanism illustrated in Figs. 1, 3, 4, and 6 and in a modified form in Fig. 8. Describing first the form 35 illustrated in Figs. 1, 3, 4, and 6, Y indicates a swinging frame or yoke the upper end of which is hung upon a heavy tubular axle or pivot-shaft Z, the ends of which latter pass through openings f in the side frames or castings J of the upper frame of the mill. The 40 openings f are made somewhat larger in diameter than the axle Z, and each is surrounded by a collar g, projecting from the face of the side frame or casting J in which it is formed. Passing radially through the collars g are adjusting-screws h, four being represented in 45 Figs. 1 and 6 for each collar. By means of these screws the ends of the axle or shaft Z can be perfectly adjusted to cause the yoke or frame 50 Y, carried by it, to swing in the precise path or plane required. Each leg of the yoke Y is formed with a split tubular barrel Y' and provided with draw-bolts i, by which to contract it, if required. Within each barrel Y' there is 55 arranged the cylindrical shank or stem j of a yoke k, in which is pivotally supported a box or bearing l, the two boxes serving to carry the shaft A' of a band-wheel B', Figs. 1 and 3. Each leg or branch of the swing frame or 60 yoke Y is formed with a projecting lug or with a cross-bar above its barrel Y', through which lug or cross-bar passes a heavy screw or bolt m, fashioned to receive a rod or lever and provided just below the cross-bar with 65 clamping-nut n and binding-nut o, as best

shown in Fig. 4. The bolts m enter holes tapped in the stems j of the yokes k and serve to move said stems inwardly or outwardly, as required, and also to hold them where adjusted. The bolts i may contribute to the 70 latter result, if found desirable; but their primary purpose is to prevent undue looseness or play. From the foregoing description it will be apparent that through the screws h adjusting the axle of swing-frame Y and through the adjusting-screws m shaft A' and wheel B' may be set or adjusted so that the latter shall run in the precise plane required. While these adjustments are deemed adequate, it is 75 obvious that any common or well-known form of adjustable bearing-blocks may be used in the yokes k to carry shaft A'. C' indicates a lever, which is here represented as composed of two rods q, q, having their upper ends riveted, screwed, or otherwise made fast in 80 ears or bosses r, formed upon the yoke or swing-frame Y near its upper or pivoted end, said rods extending thence downward parallel to each other to a point below the boxes l, where they are connected by a cross-bar s, being 85 thence carried inward or made to converge toward a medial line, their lower or outer extremities being united by a second and shorter cross-bar t, all as seen in Fig. 4 and on a smaller scale in Fig. 1. This construction, 90 which is adopted because of its combining strength and lightness, is not essential, but is advisable. The purpose of lever C' is to afford a connection for a flexible band, rope, or chain D', which after passing about a suitable guiding and supporting pulley or pulleys carries at its end a weight E' to exert a 95 constant strain or draft on lever C' and there-through upon yoke Y and its shaft A' and wheel B'. In the drawings I have shown two 100 pulleys u and v, and this I deem a desirable arrangement, though not arbitrarily required. It will be perceived readily that as the upper band-wheel P is raised and lowered as required for different logs and cants wheel B' and its 105 carrying frame or yoke Y so alter their relative positions that the wheel B' will draw upon the saw blade or band with varying advantage as to direction. Hence it is desirable to vary the leverage of the swing-frame automatically 110 and in harmony, so that the effectiveness of the wheel B' in producing tension shall be substantially uniform or constant. This result I attain by properly arranging the pivot or axle of the swing-frame Y, determining 115 its extreme range of movement and properly locating the pulley u, to which the band D' passes from lever C' of the swing-frame. By referring to Fig. 1 and carefully noting the 120 positions of the parts indicated by full and by dotted lines, which may be taken to represent very nearly the extreme adjustments, it will be seen that when wheel P is near its uppermost position the deflection of saw blade or band F' in passing from wheel I to wheel P 125 130

is relatively slight and that wheel B' moves against the blade or band in a direction at approximately a right angle to a straight line drawn tangent to the said wheels. Of course 5 this offers the greatest possible advantage for the wheel B' in applying tension to the blade; but at such time the yoke or swing-frame makes its nearest approach to a vertical position, and the distance from the pivot or axle 10 Z of the swing-frame Y to the band D' measured to the nearest point is proportionally less than when the lever C' and yoke Y are swung upward to a more nearly horizontal position. In other words, as the deflection of 15 the saw between wheels I and P decreases the effective leverage of yoke or swing frame Y decreases, and as the deflection increases and tends to reduce the effectiveness of action of wheel B in applying strain or tension, as it 20 must do because of the direction taken by the upper stretch of the saw-blade, as indicated by dotted lines in Fig. 1, the effective leverage of the swing-frame or yoke increases. This 25 will be plain upon referring to Fig. 1, where the dotted line drawn from axle or pivot Z of the swing-frame Y to the dotted line indicating band D' is seen to be about forty per cent. longer than the same line measured to the full lines representing said band D'. While this arrangement 30 does not give absolute uniformity, it nevertheless so closely approaches thereto that the variance is negligible. The device is automatic in its action, and by providing any simple means of lifting the weight E' 35 band-wheel B' may be readily dropped to permit the removal or replacement of a blade, which operation is usually performed several times during the ordinary working day. While I prefer the swing-frame or yoke thus 40 described, I do not mean to restrict myself closely thereto, as a sliding wheel-carrier may be employed instead, such, for instance, as is shown in Fig. 8. Under the construction here 45 shown the side frames J are formed with rearwardly or outwardly extending parallel arms J', each of which is provided with a guide-rod w. Upon each rod w is supported and guided a slide G', provided with barrels Y², carrying yokes j' k, in which are pivoted boxes or 50 bearings l to support the shaft A' of wheel B', all substantially as described in connection with Figs. 1, 3, 4, and 6, except for the fact that the slides G' are arranged to move longitudinally upon the rods w instead of being carried by a swinging yoke or frame. 55 The slides G' may and preferably will be connected by a cross-bar to insure simultaneous and equal movement, though the band, rope, or chain D' will be divided at a point 60 between the slides and the pulley u into two branches, extending separately to the two slides. The construction and arrangement of the slides G' is practically identical with that of the slides M, supporting the shaft O of wheel P, as illustrated in Figs. 1 and 8, the

similarity extending to the adjusting-screws X'. By giving to the arms J' a proper angle the wheel B' is caused to move in a direction approximately at right angles to a line drawn tangent to the wheels I and P on that side of the mill on which the saw blade or band passes upwardly, and hence it acts with nearly uniform effect whether the upper wheel be raised or lowered. The inclination of the arms J' is sufficient to cause the slides G' to run downward or inward by gravity when the weight E' is raised, and consequently the saw may be readily applied to and removed from the wheels, being first passed between the arms J'; but in order to do this one branch of the band or 80 rope D' must be unhooked or otherwise disconnected to enable the saw to pass out of and return into the space between the two branches. For various reasons the swing-frame construction is preferred, the mill being more symmetrical and involving less difficulty in placing or removing the saw blade or band. 85

It will be observed that although the main saw-carrying wheels I and P are of different 90 diameters the saw on the down-going or cutting side passes vertically from one to the other. In other words, their peripheries are in the same vertical plane on the log side of the mill. It is obvious, however, that, if desired, the upper and lower wheels may be made of like diameters. By slightly reducing the diameter of the upper wheel, however, I am enabled to make the wheels P and B' of the same or substantially the same diameter, and 95 while this is not essential it is desirable that the wheel B' be made approximately as large as the wheel P in order that the saw blade or band may pass about it without undue bending and may be subject to the same degree 100 and character of resistance or drag, if any there be, upon each wheel.

I am aware that it is not broadly new to carry the blade of a band-saw mill about three 110 wheels, one of which is adjustable to provide or maintain tension upon the blade; but so far as I am aware no one has before constructed a mill of this type with an upper wheel adapted to rise and fall through a range sufficient to bring it close to the smallest log or cant 115 and to carry it clear of the largest log or cant and combined therewith means for taking up the slack of the saw and maintaining adequate tension under all adjustments.

By my construction I am enabled to dispense entirely with the upper saw-guide and to give to the saw proper guidance, tension, and support under all adjustments of the mill. So far as I am aware this result has not hitherto been accomplished in a mill having the lower 125 or main driving-wheel carried in normally fixed boxes or bearings.

It is particularly to be noted that under my construction the upper wheel has a right-line movement and cannot twist or get out of 130

proper plane, and it will also be seen that the bearings for all the wheels are so supported that any chattering, shifting, or movement thereof, except movement incident to making

5 of the adjustments by means provided for that purpose, will be avoided. It is essential in machinery of this sort that the construction be as rigid as possible, owing to the tremendous strains to which the parts are subjected, 10 to the rapidity of movement of the saw blade or band, and to the disarrangement of parts which would occur upon the breakage or running off of the saw or blade if the parts were not firmly held in position and prevented from 15 shifting or jumping from place.

Having thus described my invention, I claim—

1. In a band-saw mill, the combination of a main frame; a main driving-shaft carried in 20 normally fixed bearings in said frame, and provided with a saw-carrying wheel; a second shaft carried in vertically-movable supports on said frame, and provided with a saw-carrying wheel; means for adjusting and holding 25 said supports; a swing-frame pivoted or hung in the main frame; an adjustable pivot shaft or axle for said swing-frame; a saw-supporting wheel carried by said swing-frame; and means for urging said wheel outward 30 against the up-going side of the saw-blade, substantially as described.

2. In a band-saw mill, the combination of a main frame; a main saw carrying and driving wheel having its shaft mounted in normally 35 fixed boxes or bearings; a second saw-carrying wheel vertically adjustable with reference to the cutting-point; a swing-frame hung or pivotally supported in the main frame, and provided with a third saw-supporting wheel; 40 and means substantially such as described for bringing said third wheel into proper plane relatively to the saw-carrying wheels and the saw.

3. In combination with the main frame of a 45 band-saw mill and with upper and lower saw-carrying wheels; a swing-frame mounted in the main frame and provided with separated journal boxes or bearings; an adjustable pivot or axle for said swing-frame; means for adjusting 50 the journal boxes or bearings carried by said frame; a shaft journaled in said boxes or bearings; a saw-carrying wheel carried by said shaft; and means for urging or pressing said wheel against the saw-blade.

55 4. In combination with the main frame and upper and lower saw-carrying wheels of a band-saw mill; a pendulous or swinging frame mounted in the main frame; a pivot shaft or axle for said swinging frame carried at its ends 60 in enlarged openings in the main frame; adjusting devices acting upon the ends of said shaft or axle and serving to adjust and hold the same; shaft boxes or bearings carried by the swinging frame; adjusting devices applied to 65 said boxes or bearings and serving to move

them toward or from the pivot-axis of the frame; a shaft journaled in said boxes; and a saw-carrying wheel mounted upon said shaft, all substantially as described and shown.

5. In combination with the main frame and 70 upper and lower saw-carrying wheels of a band-saw mill; a pendulous frame hung or pivoted in the main frame and provided with a third saw-supporting wheel; a pulley located above said swinging frame; and a flexible band 75 passing about said pulley connected at one end with the swinging frame and provided on the other side of said pulley with a weight or straining device, the location of the pulley being such with reference to the pivot-axis of 80 the swinging frame and to the upper and lower saw-carrying wheels that as the effective pressure of the wheel against the saw-blade decreases, the effective leverage of the swinging frame increases and vice versa. 85

6. In a band-saw mill, the combination of a main frame; a main saw carrying and driving wheel having its shaft journaled in normally fixed boxes or bearings; a second saw-carrying wheel movable vertically to bring it close 90 to logs or cants of different size; a third saw-carrying wheel movable independently of the second; and means substantially such as described and shown whereby said third wheel is caused to exert a practically uniform strain 95 or tension upon the saw-blade.

7. In combination with the base and side plates or frames of a band-saw mill, a strut or truss connecting said frames and having inwardly-extending bracing-arms, substantially 100 as described and shown.

8. In combination with base A and side plates or frames J, connecting brace or strut K having necks extending through and secured in openings in the side frame and provided with inwardly-extending bracing-arms, substantially 105 as shown.

9. In combination with the base A, side plates J and brace K, and with upper and lower saw-carrying wheels; swinging frame Y hung 110 in said main frame and provided with a saw-carrying wheel substantially as shown and described.

10. In combination with the main frame of a band-saw mill, and with upper and lower 115 band-carrying wheels; a swinging frame hung in the main frame and provided with a third saw-carrying wheel; a lever C' attached to said swinging frame and comprising rods q and cross-bars s and t; and a weighted band 120 connected with the outer end of said lever C', and serving to move the swinging frame upwardly and outwardly.

11. In a band-saw mill, the combination with the main frame, driving shaft and wheel; 125 of vertically-movable slides M provided with vertical sleeves or boxes and with brackets e; vertically-adjustable yokes X mounted in said sleeves or boxes; adjusting-screws X' for said yokes; journal boxes or bearings carried by 130

the yokes; a shaft mounted in said boxes or bearings; and a saw-carrying wheel mounted upon said shaft, substantially as shown.

12. In combination with the main frame and carrying-wheels and shaft of a band-saw mill; slides M movable vertically upon guides or ways of the main frame; a cross-shaft Q carried in bearings in said slides and provided with pinions *a* and with worm-wheel R; a bracket, shell or casing S carried by one of said slides; a worm or screw T meshing with the worm-wheel R and carried in said bracket shell or casing; and a shaft U passing freely

through the worm or screw T but incapable of rotation independently thereof, whereby ¹⁵ the slides M and the shaft and wheel carried by them may be raised or lowered and held at any desired elevation.

In testimony whereof I have signed my name to this specification in the presence of two sub- ²⁰ scribining witnesses.

GEORGE M. HINKLEY.
